KURT LIGNIEZ, OF MANNHEIM, GERMANY.

INLET CONTROL FOR RECIPROCATING ENGINES.

Application filed October 10, 1923. Serial No. 667,611.

To all whom it may concern:

Be it known that I, KURT LIGNIEZ, a citizen of Germany, residing at Mannheim, Badenia, Germany, have invented new and 5 useful Improvements in Inlet Controls for Reciprocating Engines, of which the following is a specification.

This invention relates to an automatic inlet valve mechanism for reciprocating engines in which a cut-off member positioned to normally open an inlet is actuated by throttling the working fluid to close the inlet.

The object of the present invention is a 15 mechanism which will start, operate and stop the engine by means of the throttle-valve lever, moreover, to obtain small steam volumes with full inlet pressure, further, to govern the engine speed by automatically cutting off the steam supply.

The present invention consists of the novel combination of an automatic inlet valve mechanism, whose cut-off member is actuated by throttling of the working vapor, 25 with a slide valve which accomplishes the function of inlet lead, cut-off, exhaust lead, and compression in the usual manner, but which relieves the automatic inlet valve mechanism of pressure in an entirely new 30 way, thus opening it.

In all heretofore known types of automatic inlet valve mechanisms opening of the inlet was accomplished either by exceedingly high compression, which necessarily 35 used to equal the inlet steam pressure, or by means of inlet-valves, which were opened by the piston just before dead center, in order to fill the clearance space with live steam.

40 The automatic inlet-valve is relieved by uncovering a port leading to the steam-chest, and admitting a small volume of high-pressure steam. The area of this port may be so reduced that the inlet-steam has insufficient time to reseal the inlet-valve mechanism, which then remains tightly shut, producing a number of extremely effective suspension strokes of the slide valve, because under these conditions no steam is admitted 45 to the clearance space. The inlet-valve mechanism does not again open until the engine speed has decreased considerably.

The invention resides more particularly in

the novel combinations hereinafter described and claimed, reference being made to the 55 accompanying drawing in which:—

Fig. 1 represents a vertical section of a portion of a steam engine showing the preferred form of the invention.

Fig. 2 illustrates various diagrams.

Referring to Fig. 1 of the drawing, the steam enters the steam chest 5 by means of the inlet port 16 and passes under the end of the spring plate 6 and into the inlet-port 7 which remains filled with steam as long as 65 the spring plate is open. The slide-valve 8 permits the steam to pass through the port 9 into the cylinder 10 and it is exhausted through an outlet port 17 from the steam chest. The piston 11 moves with increasing 70 velocity from head end dead center toward its midstroke position, meanwhile the steam is subjected to constantly greater throttling until, let us say, at 15% cut-off, the excess inlet-steam pressure on the end of the 75 spring-plate closes the inlet-port 7. In the meantime the ports controlled by the slide-valve stay open up to 80% cut-off volume without the additional admission of any live steam.

80 As soon as the slide-valve has closed port 9 the relief port 13 connecting the cylinder with the steam chest is opened and sufficient live steam enters, the end of the automatic inlet-valve is released and opens port 7. 85 After the inlet port 7 has been closed the port 9 remains open for a brief space to allow the spaces 7 and 9 to take part in the expansion of the steam in the cylinder producing reduced pressure. This reduced 90 pressure allows the inlet-valve mechanism to remain closed until the relief port 13 has been opened. If the relief port is sufficiently small, the steam will not have time enough to release the spring-plate at the maximum 95 rotational speed. The spring-plate remains closed temporarily and all steam is cut off until the speed drops.

100 In Fig. 2 a diagram 1 is shown denoting the start with full stroke cut-off and greatly throttled inlet steam pressure, while diagram 2 shows the action with fully opened throttle valve, full inlet steam pressure and approximately 20% cut-off. Diagram 3 shows the suspension of a charge due to the 105 rapid inflow of steam into the clearance

space of the cylinder at the moment when the maximum permissible rotational speed has been attained.

By combining the automatic inlet-valve

5 mechanism with a slide valve reversing is accomplished with a single movement of the reversing lever, starting takes place by moving the slide-valve lever, gradually at first, it being fully opened only after the 10 engine has reached a certain rotational speed. The high pressure steam, acting together with a sufficiently high engine speed then automatically produces cut-off at the inlet-valve.

15 The higher the rotational speed the earlier the cut-off, consequently the machine, even with nonadjustable spring-gab and with widely varying engine loads soon reaches a state of rotational stability which lies

20 within limits permissibly close to the normal rotational speed.

A salient new feature is the suspension of steam admission to the cylinder at and beyond that point where the engine exceeds 25 its highest permissible rotational speed. This is effected by the combination of the automatic inlet-valve mechanism and the slide-valve. At the beginning of inlet lead the clearance space is only partly filled with 30 steam thus the steam flows into the clearance space with a certain velocity during the period of inlet lead and may be so throttled in the spring clearance gab, according to the rotational speed of the engine, that even if the piston is on dead cen- 35

ter the inlet-valve mechanism is closed, therefore when the engine exceeds a certain speed the steam-supply is completely cut off. Strokes with smaller and larger partial cut-off volumes then alternate with strokes 40 during which steam is completely cut off.

I claim:—

1. An inlet control for reciprocating engines comprising a chest with a steam inlet, a chamber provided with a slide valve, an inlet port in the steam chest communicating with the chamber, a cut-off plate arranged in the steam chest to normally open the inlet port, and a relief port located in the wall of the slide valve chamber leading 50 from the steam chest into the chamber opened by the side valve when the inlet is closed so as to relieve the pressure on the plate to open the port.

2. An inlet control for reciprocating engines comprising a chest with a steam inlet, a chamber provided with a slide valve, an inlet port in the steam chest communicating with the chamber, a cut-off spring plate arranged in the steam chest to normally open 55 the inlet port and close it by flexing the plate, and a relief port located in the wall of the slide valve chamber leading from the steam chest into the chamber opened by the slide valve when the inlet is closed so 60 as to relieve the pressure on the spring plate to open the port.

In testimony whereof I have hereunto set my hand.

KURT LIGNIEZ.
